Inventor:

Henry K. Sandell,
By appointment to the
Christian Willis,
Att'y Gen.

UNITED STATES PATENT OFFICE.

HENRY K. SANDELL, OF CHICAGO, ILLINOIS.

SOUND-REPRODUCING APPARATUS.

1,399,403.

Specification of Letters Patent.

Patented Dec. 6, 1921.

Application filed October 3, 1919. Serial No. 328,229.

To all whom it may concern:

Be it known that I, HENRY K. SANDELL, a citizen of the United States, residing at 221 South Green street, Chicago, in the 5 county of Cook and State of Illinois, have invented a new and useful Improvement in Sound-Reproducing Apparatus, of which the following is a specification.

The present invention relates to apparatus for reproducing sounds, and more particularly to apparatus wherein a plurality of vibratory diaphragms may be actuated independently and simultaneously by a single reproducing needle or stylus to produce different series of sound waves.

An apparatus embodying the present invention is illustrated in the accompanying drawings, in which—

Figure 1 is a side elevation, partially in section, of a device constructed in accordance with the present invention.

Fig. 2 is an end elevation, partly in section on line 2—2 of Fig. 1 of the reproducing mechanism, the parts thereof embodying the 25 diaphragm supports not being shown;

Fig. 3 is a vertical section on the line 3—3 of Fig. 1; and

Fig. 4 is a plan view of the amplifiers, being taken in section through the conduits 30 leading thereto.

In my application for patent, filed Oct. 3d, 1919, Serial No. 328,230, I have described a sound record formed with a groove the bottom of which is formed with waves 35 of the hill and dale type, recording a succession of sound waves, and the side of which are formed with lateral waves, recording independently a different succession of sound waves. In the form of construction illustrated in the drawings it is assumed that the sound waves recorded upon such a record are to be reproduced.

Referring more particularly to the drawings, the numeral 10 indicates a support or 45 table through which passes a rotatable shaft 11 carrying a flat table 12 upon which rests the sound record 13 containing record grooves of the type described. The shaft 11 may be rotated by any suitable means, not 50 shown.

The reproducing stylus is carried by oscillatable arm 14, the mounting of which will be hereinafter described. Its end 15, which swings over the record 13, is suitably formed 55 to carry the pivotally mounted plate or lever element 16. This plate rests upon hori-

zontally spaced pivot pins 17, 17 and is retained movably in position upon said pins by helical springs 18 interposed between the said plate and the heads of screws 19, 19. 60 Plate 16 is thus capable of oscillation relative to the end 15 of arm 14 about a horizontal axis or fulcrum, the line joining pivot pins 17, 17.

Upon the plate 16 is mounted a plate or 65 lever element 20 for the stylus, this plate resting on two vertically spaced pivot pins 21, 21 which project from the plate 16. Plate 20 is retained movably in position by helical springs 22, 22 interposed between the plate 70 20 and the heads of screws 23, 23, which pass through suitable openings in plate 20 to plate 16. Suitable openings 24, 25 may be provided in plate 20 to permit free passage of the heads of screws 19, 19. Plate 20 is, 75 as is readily apparent, capable of oscillatory or rocking movement relative to plate 16 and to the end 15 of arm 14 about the fulcrum line joining pivot pins 21, 21 as a vertical axis. The stylus support 26 projects forwardly and slightly downwardly 80 from plate 20, stylus 27 being retained therein by any suitable means, such as set screw 28.

The movements of plates 16 and 21 are 85 transmitted to the diaphragms of separate sound boxes, for example, as follows: The plates 16 and 21 may be provided respectively with tongues 29 and 30, tongue 29 projecting vertically from plate 16 and tongue 90 30 projecting horizontally from plate 21. From tongue 29 a vibration transmitting member 31, which may be, for example, a wire 31, extends to diaphragm 32 of sound box 33, being attached thereto at an acute 95 angle preferably less than 45°. In the device illustrated an angle of about 22° is shown. In a similar manner a vibration transmitting member 34 extends from tongue 30, joining diaphragm 35 of sound box 36 100 at an acute angle. The sound boxes 33 and 36 are retained in relative position by a suitable frame member 37, which may also suitably serve for the attachment of the arm 14.

From the sound boxes 33 and 36 there extend 105 in opposite direction and preferably in vertical alignment the conduit sections 38 and 39. Conduit section 38 is journaled on the downward opening of the curved conduit section 40 and conduit section 39 is journaled 110 on the upwardly projecting coupling 34 of the fitting 42. The arm 14, together with

the sound boxes 33 and 36 are hence capable of oscillating about the vertical axis of conduit sections 38 and 39.

The curved conduit section 40 is connected 5 to a rearwardly projecting coupling 43 of fitting 42. Fitting 42 is rotatably journaled at its ends in elbows 44 and 45, and is provided internally with a partition 46 so arranged that the waves issuing from sound 10 box 33 through conduit 40 pass out through elbow 44 and those issuing from sound box 36 pass out through elbow 45. Elbows 44 and 45 communicate respectively with the ends 46 and 47 of the twin horns or amplifiers 15 48 and 49. The elbows 44 and 46 are supported in position by flanges 50, 50 suitably attached to the support 10. It is readily apparent from the construction described that the arm 14 is capable of a limited vertical oscillation, together with the sound boxes 20 33 and 36 and the associated fittings.

In the operation of the device of the present device in conjunction with a sound record 13 mounted upon the table 12 and having 25 a record groove, the bottom of which has a vertical wave conformation and the sides of which have a lateral wave conformation, it is apparent that the vertical waves of the bottom of the groove will produce oscillations of plate 16 about its vertical axis, thereby actuating diaphragm 32 and without affecting diaphragm 35. Similarly, the lateral waves of the sides of the record groove will produce oscillations of plate 20 about its 30 vertical axis, thereby actuating diaphragm 35 without affecting diaphragm 32. For accurate operation it is preferred that the point of attachment of transmission wire 31 to plate 16 be collinear with the axis of oscillation of plate 16 and that of attachment of transmission member 34 to plate 20 be collinear with the axis of oscillation of plate 16.

It is furthermore apparent that the present reproducer may be used without change 45 of position in conjunction with records containing grooves of the usual hill and dale type or with those containing grooves of the vertical wave type, one diaphragm only re-

sponding to the vibratory movement of the 50 needle or stylus produced in each case.

In order that the sounds issuing from either or both amplifiers may be modulated or controlled at will, dampers 50, 50 may be inserted in conduits leading thereto. These 55 may be regulated independently to secure any desired modulation of the sounds issuing from the amplifiers.

Although the present invention has been described and embodied in a particular form 60 of apparatus, it is not intended that the details of construction and operation set forth shall be regarded as limitations upon the scope of the invention, except in so far as included in the accompanying claims. 65

I claim:

1. In sound reproducing apparatus, a support, a lever mounted thereupon for oscillation about a horizontal axis, a sound producing diaphragm, a link connecting the 70 lever to the diaphragm, a second lever mounted upon the first mentioned lever for oscillation therewith about its horizontal fulcrum but oscillatable relatively thereto about a vertical axis, a second sound producing diaphragm, a link connecting the second lever to the second diaphragm, and a stylus holder rigidly connected with the 75 second lever.

2. In sound reproducing apparatus, a support, a lever mounted thereupon for oscillation about a horizontal axis, a sound producing diaphragm, a link connecting the lever to the diaphragm, a second lever mounted on the first mentioned lever for oscillation therewith about its horizontal fulcrum but oscillatable relatively thereto about a vertical axis, said vertical axis passing through the point of connection of the above mentioned link, a second sound producing diaphragm, a link connecting the second lever to the second diaphragm, the point of connection of the said link being alined with the horizontal axis of the first mentioned lever, a stylus holder rigidly connected with the 85 second lever. 90

HENRY K. SANDELL.
